V. MATRANGA, DEC'D.
V. MATRANGA, ADMINISTRATRIX.
CONFECTION COATING MACHINE.
APPLICATION FILED APR. 27, 1920.

1,420,436.

Patented June 20, 1922.

UNITED STATES PATENT OFFICE.

VINCENZO MATRANGA, OF NEW YORK, N. Y.; VINCENZA MATRANGA ADMINISTRATRIX OF SAID VINCENZO MATRANGA, DECEASED.

CONFECTION-COATING MACHINE.

1,420,436.

Specification of Letters Patent. Patented June 20, 1922.

Application filed April 27, 1920. Serial No. 377,032.

To all whom it may concern:

Be it known that I, VINCENZO MATRANGA, a citizen of Italy, and a resident of the city of New York, borough of Manhattan, in the 5 county and State of New York, have invented a new and Improved Confection-Coating Machine, of which the following is a full, clear, and exact description.

The present invention relates to new and 10 useful improvements in confectioners' machines, and it pertains more particularly to a machine especially adapted for coating cakes, candies and similar confections.

It is an object of the present invention to 15 provide a new and improved mechanism for subjecting or submerging the confections to be coated in the material with which they are to be coated.

It is another object of the invention to 20 provide a machine in which the confections to be coated are momentarily maintained submerged.

It has been found to be advantageous to 25 move the receptacle in which the coating material is carried to a position where it will submerge the confections, and it is a further object of the present invention to so construct a machine of this character as to efficiently carry out this operation.

30 It is a still further object of the invention to so construct the device that it may be used on machines as at present employed for the purpose of coating confections.

35 With the above and other objects in view, reference is had to the accompanying drawings, in which—

Figure 1 is a view partly in section and 40 partly in end elevation of the front portion of a machine constructed and arranged in accordance with the present invention;

Fig. 2 is a side elevation of the front portion of said machine;

Fig. 3 is a detail sectional view of the 45 mechanism employed for maintaining the confection submerged within the material with which they are coated;

Fig. 4 is a top plan view partly in section taken on the line 4—4 of Fig. 3.

50 Referring more particularly to the drawings, the mechanism is carried by a suitable framework consisting of vertically disposed side stanchions or frames 10 connected by horizontally extending beams 11. Mounted 55 at suitable points within this framework are shafts 12, and each of said shafts car-

ries near each end thereof, a sprocket wheel 13. Traveling over the sprocket wheels 13 are chains 14 and these chains 14 form an endless conveyer by means of which the confections are carried through the machine. At spaced points throughout the length of each of the chains 14 are pins 15, and said pins 15 serve as a support or attaching means for racks 16. These racks 16 are provided 60 with prongs or pointed fingers, said fingers projecting at right angles from a transversely extending bar 17, and said fingers serve as the means for supporting the confections 18.

To provide for the driving of the chains or conveyer 14, a motor 20 is suitably positioned with respect to the framework of the machine, and through the medium of a belt 21 which passes around the driving pulley 70 22 of said motor and the main power pulley 23 of the machine, it will be seen that the necessary power is applied to drive the conveyer or chains 14, since these chains 14 pass into engagement with the sprocket wheel 23 75 shown in dotted lines at the lower portion of Fig. 2.

Extending transversely of the machine is a shaft 25, and on each end of said shaft 25, is a sprocket 26. Mounted below the 80 shaft 25 is a shaft 27, and upon each end of the latter shaft there is a sprocket 28. Mounted to the rear of the shafts 25 and 27, is a third shaft 29, and carried by this shaft 29 are sprocket wheels 30. Passing around 85 the sprocket wheels 26, 28 and 30, at each side of the machine, is a chain 31, and this chain serves the means by which the shafts 27 and 29 are driven from the shaft 25, it being understood that said shaft 25 is driven 90 by the chains 14 passing around the sprockets 13 carried by the shaft 25.

The reference character 35 designates a receptacle for containing the material with which the confections are to be coated, and 100 this receptacle 35 is carried upon a table 36. The table 36 is mounted in guideways 37 in the framework in such a manner as to be capable of vertical movement therein. For imparting vertical movement to the table 36, the shaft 27 is provided near each 105 of its ends with cams 38, and these cams are adapted to engage blocks 39 on the bottom face of the table 36 to raise and lower the same as the shaft 27 is rotated.

As shown in Fig. 1, guide blocks 40 are 110 suitably mounted one on each side of the

machine, and mounted in each of these guide blocks in a manner to provide for vertical movement, is a shaft 41. This shaft 41 is provided with a spiral groove 42, and engaging said spiral groove 42 and carried by the block 40, is a pin 43. To impart vertical movement to each of the shafts 41, the shaft 29 is provided near each end, with a cam 44, and each of said cams is adapted to engage the rear of a lever 45, it being understood that there is one lever for each of the cams 44. Each of these levers 45 is pivoted as at 46, to the frame, and each lever is adapted to engage at its forward end with 15 its respective vertical shaft 41.

Surrounding each shaft 41 and engaging at its upper end with its respective block 40, is a spring 47, the lower end of said spring being secured to the shaft as at 48. The 20 upper end of the shaft 41 is bent at right angles as indicated by the reference character 50, and said right-angular portion 50 is again bent at right angles as at 51, from the outer end of which the shaft is bent downwardly as indicated by the reference character 52, and is bent again at right angles as indicated by the reference character 53. By this construction, it will be seen that as 25 the shafts 41 are moved vertically through their respective blocks 40, the shafts 41 will be given a rotary movement, which movement will cause the shafts to travel in and out of the receptacle as shown by dotted lines in Fig. 4. It is to be understood, however, that the cams 44 will operate in advance of the cams 38 in such a manner that the right-angular extremity 53 of the shaft 41 will engage the cross bar 17 of the confection carrier before the receptacle 35 has 30 been moved vertically to the position where the confections are submerged, and said right angular extension 53 is not moved to the dotted line position in Fig. 4 until the receptacle 35 has been lowered.

45 The device operates in the following manner:

The operator stands on the platform 60 in front of the receptacle 35 and positions the confection carriers or racks 16 upon the pins 15 as the same present themselves at 50 the front of the machine. The confection carriers 16 are so positioned on the chain conveyor 14 as to be engaged as they move downwardly by the right-angular extremity 53 of the downwardly moving shaft 41 and move while so engaged without being held against movement occasioned by the operation of the chain conveyor until such time as the cams 38 operate to elevate the table 60 36 and the receptacle 35 to the position shown in Figure 1, in which position the confections 18 are submerged, being prevented from rising independently of actuation by the chain conveyor to the surface of

the heavy coating material in the receptacle 65 by the engagement of the extremity 53 with the confection carriers 16. The cams 38 now operate to lower the table 36 and the cams 44 operate to move the right-angular extension of the shaft 41 out of engagement 70 with the bars 17 of the carriers 16 in order that there may be no interference with such movement of the carriers 16 as is occasioned by the operation of the chain conveyor 14, whereby such carriers may pass on to the 75 rear of the machine where they are removed from the conveyor 14.

By this construction it will be seen that the container for the coating material is moved vertically with respect to the carrier 80 or conveyer in which the confections are carried and at the same time means is provided for maintaining the confections submerged within the coating material carried by said receptacle. Furthermore, owing to the vertical movement of the shafts 41 together with the rotary movement imparted thereto, the means by which the confections are maintained in submerged position is free to rotate if properly timed in such a manner 85 as to clear the sides of the receptacle 35 in its operation.

What is claimed is:

1. In a machine for coating confections, a suitable support, an endless conveyer traveling through said support, a plurality of confection-carrying racks carried by said conveyer, a coating-material receptacle, means operated from said conveyer for periodically elevating the coating-material receptacle, 95 and means adapted for engagement with the confection-carrying racks for maintaining said racks submerged in the coating material in the receptacle when the latter is in elevated position.

2. In a candy-coating machine, in combination, a coating-material receptacle, means for introducing the articles to be coated into said receptacle, means for elevating the receptacle to submerge the articles to be coated, and means for maintaining said articles to be coated in submerged position within the coating-material receptacle.

3. In a confection-coating machine, in combination, a coating-material receptacle, means for carrying a plurality of articles to be coated and positioning them about the coating-material receptacle, means for elevating the coating-material receptacle to 115 submerge the articles to be coated, and means intermittently operated and movable into and out of the coating-material receptacle to maintain the articles to be coated 120 momentarily submerged in the material carried within the coating-material receptacle.

VINCENZO MATRANGA,
